UNITED STATES PATENT OFFICE.

JULIUS GEBAUER, OF PHILADELPHIA, PENNSYLVANIA, ASSIGNOR TO
JOSEPH GREER, OF SAME PLACE.

DESIGN FOR A PATTERN FOR CLOTH FABRIC.

SPECIFICATION forming part of Design No. 20,177, dated September 30, 1890.

Application filed August 14, 1890. Serial No. 362,036. Term of patent 3½ years.

To all whom it may concern:

Be it known that I, JULIUS GEBAUER, a subject of the Emperor of Germany, but now residing at the city of Philadelphia, in the county 5 of Philadelphia and State of Pennsylvania, have invented and produced a new and original Design of a Pattern for Cloth Fabrics, of which the following is a specification, reference being had to the accompanying drawing, 10 forming part hereof, and which shows the design of the pattern embodying the particular characteristic features of my invention.

The leading features of my design or pattern for a cloth fabric consist, broadly, of 15 numerous block-like configurations, presenting in appearance in the fabric broken stripes, columns, or ribs arranged in diagonal courses, and block-like configurations arranged in similar courses adjacent thereto within and 20 throughout the same.

Referring to the accompanying drawing, forming part hereof, *a* represents each of a series of block-like configurations, (in white in the illustration,) composed of one material 25 arranged in broken diagonal rows of courses *A* and forming the stripes or ribs of the fabric. *b* represents each of a series of similar block-like configurations, (in black in the illustration,) composed of another material, ar-

ranged in similar rows or courses *B* adjacent 30 to or adjoining the rows or courses *A*, having, respectively, zigzag contours. *c* represents each of four block-like configurations constituting the filling woven, or otherwise disposed in diagonal rows or courses between those 35 designated by the letter *B*. The respective materials closely mesh with one another in such manner as that the material of an inferior nature is not exposed to view upon the face of the fabric, but forms the body of the 40 fabric, while the other material appears prominently within and throughout the fabric in broken diagonal stripes or ribs—for example, in the manner illustrated.

Having thus described the particular features of my design, what I claim as new, and desire to secure by Letters Patent, is—

A design or pattern for a cloth fabric, such as hereinbefore described, and illustrated in the accompanying drawing. 50

In witness whereof I have hereunto set my signature in the presence of two subscribing witnesses.

JULIUS GEBAUER.
